UNITED STATES PATENT OFFICE.

AL HERBERT LAMB, OF ELBON, PENNSYLVANIA.

MUSIC-LEAF TURNER.

SPECIFICATION forming part of Letters Patent No. 729,944, dated June 2, 1903.

Application filed June 21, 1902. Serial No. 112,645. (No model.)

To all whom it may concern:

Be it known that I, AL HERBERT LAMB, a citizen of the United States, residing at Elbon, in the county of Elk and State of Pennsylvania, have invented a new and useful Music-Leaf Turner, of which the following is a specification.

This invention relates to combined book-holders and leaf-turners, and is designed to provide an improved device of this character which is especially applicable to pianos for supporting book and sheet music in position to be conveniently read by the performer and also having means for successively turning the leaves of the music in a convenient and effective manner.

It is furthermore designed to arrange for mounting the device upon the music rack or support of a piano in such a manner as to prevent looseness and displacement of the device by the manipulation of the leaf-turning means and also to have the holding means adjustable, so as to accommodate the device to pianos of different sizes.

Another object is to provide for mounting the leaf-turning arms so that the throw of each arm is equal to the throw of each of the other arms in order that there may be a uniform turning of the leaves and to prevent displacement of the leaves from the arms.

Another object is to arrange the arm-manipulating devices in compact relation and in convenient reach of the performer without interfering with the passage of the hands over the keyboard.

Another object is to have the leaf-turning arms adjustable in order that they may be accommodated to the varying widths of leaves.

With these and other objects in view the present invention consists in the combination and arrangement of parts, as will be hereinafter more fully described, shown in the accompanying drawings, and particularly pointed out in the appended claims, it being understood that changes in the form, proportion, size, and minor details may be made within the scope of the claims without departing from the spirit or sacrificing any of the advantages of the invention.

In the drawings, Figure 1 is a perspective view of an upright piano, showing the present device applied thereto. Fig. 2 is a detail ele-

vation of the back of the device. Fig. 3 is a detail view with the front of the piano in section and the combined holder and turner in side elevation to show the manner of fitting the device to a piano. Fig. 4 is an enlarged front elevation of the lower portion of the body of the holder to show the leaf-turning means. Fig. 5 is a vertical section thereof on the line 5 5 of Fig. 4. Fig. 6 is a plan view of the leaf-turning means with the back or body of the holder in section. Fig. 7 is a horizontal cross-sectional view to show the mounting of the manipulating-keys. Fig. 8 is a detail sectional view of one of the leaf-turning arms to show the telescopic construction thereof.

Like characters of reference designate corresponding parts in all of the figures of the drawings.

For an understanding of the supporting or holding feature of the present invention reference is had at first more particularly to Figs. 1 to 3 of the drawings, wherein the reference character 1 designates the back or body of the device, which is in the form of a rectangular plate or board, which may have any preferred ornamental or attractive shape. Extending longitudinally across the back of the body is a pair of longitudinal notched or slotted cleats 2, which, besides stiffening the board and preventing warping thereof, also form guides for an endwise-shiftable bar 3, which is designed to be projected or extended above the top of the board to form an extensible support for the upper end thereof in order that the device may be fitted to pianos of different sizes, as will be hereinafter explained. A set-screw 4 pierces the upper portion of the body and engages the extensible bar 3, so as to hold the same against accidental endwise movement after being adjusted. Near the lower end of the body is a looped or substantially U-shaped spring 5, the opposite end portions of which are bent back into attaching-arms 6, which are secured to the back of the body by means of suitable fastenings 7, the intermediate portions of the spring between the sides thereof and the respective arms 6 being formed into spring-coils 8.

In applying the device to a piano, as shown in Figs. 1 and 3, the upstanding ledge at the

outer edge of the music rack or rail 9 of the piano is received between the spring 5 and the back of the body of the device, and the bar 3 is adjusted to fit between the pendent ledge at the outer edge of the top 10 of the piano and the front 11 thereof. When thus applied, the spring 5, which has a comparatively long intermediate portion resting upon the music rack or rail 9, forms a stable support for the lower end of the device and also snugly grips the ledge of the music-rail between the spring and the body 1, so as to guard against looseness and accidental displacement of the body, while the upper end 15 of the bar 3 is seated between the front of the piano 11 and the ledge upon the top of the piano and is thereby held against displacement.

The leaf-turning means comprises a plurality of substantially horizontally-swinging arms 12, which are arranged in stepped series one in front of the other, all of the arms being equal in length and swinging in parallel planes. Each arm is provided at its inner 20 end with a pendent journal or shaft 13, which pierces the top and bottom of a box or casing 14, secured to the front of the body and projected slightly below the latter. The openings in the top and bottom of the casing 25 which receive the shafts also form bearings therefor, the lower ends of the shafts being stepped in the bottom of the casing, as best illustrated in Fig. 5, so as to support the shafts. Each arm is made extensible, so as to 30 accommodate the device to leaves of different widths by means of an outer tubular section 15, which telescopes upon the outer end of the arm, as best indicated in Fig. 8. At the outer end of the tubular section 15 are a pair 35 of spaced upstanding substantially parallel spring-fingers 16, which are designed to embrace a leaf, so as to connect the arm thereto, wherefore it is apparent that the fingers 16 form a bifurcated seat to receive the lower edge 40 of a leaf. The fingers 16 are preferably elastic and separated by a space slightly less than five times the thickness of a leaf in order that the latter may be held between the fingers and that the leaf may not pull through the space between the fingers when being turned. When 45 the arms are in their initial positions—that is to say, at the right-hand side of the device—they are braced by means of a stepped support 17, rising from the top of the casing and provided with stops or a succession of 50 shoulders gradually increasing in height, according to the height of the arms above the top of the casing. This stepped support is best illustrated in Figs. 5 and 6, from which it is apparent that the support takes the strain from the shafts or journals of the arms and the upstanding shouldered portions form stops to limit the movements of the arms toward the body and to maintain the same in 55 parallel relation, so that they may not interfere with one another. It will here be noted that the stepped support is at the right-hand

side only of the device, as it is desired to permit the arms to swing as far back as possible toward the body when thrown to the left side 70 thereof in order that the leaves may lie as flat as possible. To provide for the convenient manipulation of the arms by rotating the shafts or journals 13, the latter are provided with pinions 18, which are disposed one above 75 the other, preferably with the pinion upon the outermost shaft disposed near the lower end thereof, with the other pinions disposed in regular succession in higher horizontal planes. Each pinion is controlled by two 80 keys 19, which are in the form of endwise-shiftable bars located at opposite sides of the pinion in the same horizontal plane therewith and having their inner sides provided with teeth 20 in mesh with the pinion. Each 85 of these keys or rack-bars is preferably polygonal in cross-section and works through a correspondingly-shaped opening 21 in the front of the casing or box 14, the outer end of the bar being provided with a finger-piece 22 90 and its inner end having a longitudinal bore or socket 23 to telescopically receive a guide stud or pin 24, rigidly carried by the back of the casing so as to guide the inner or rear end of the bar and to maintain the toothed portion thereof in mesh with the pinion. It will 95 be noted that the back of the box or casing forms a stop to limit the inward or rear movement of each key or bar, and as the pinion is stopped simultaneously with the inward or 100 rearward movement of the key the outward movement of the opposite key is always stopped at the same time and is therefore prevented from being displaced from the pinion and the casing. By having two keys for 105 each pinion one of the keys is always projected and in position for manipulation to throw the corresponding arm, and therefore the keys are manipulated by pushes instead of by pulls, which is a very important advantage, as a pull upon one of the keys would tend to displace the device from the piano. 110

For the support of the music upon the back or body 1 a plurality of pins or projections 25 are applied to the body and aligned transversely across the same just above the uppermost arm 12 and below the tops of the spring-fingers 16, so as to support the lower edges of the leaves of music in convenient position to be engaged with the fingers. The 115 pins 25 are so arranged that the fingers 16 may swing between a pair of adjacent pins, so that the latter may not interfere with the leaf-turning means.

A pair of upstanding spring-arms 26 are 125 secured to the lower portion of the front of the body and are disposed at opposite sides of the casing 14, with their upper ends projected above the row of pins 25 and adapted to overlap and bear against the leaves which 130 are not to be turned in order that the book or other piece of music may be held substantially rigid during the turning of the loose leaves.

In using the present device the body thereof is fitted to the piano, as hereinbefore described, and then the book or other piece of music is applied to the back or body and supported upon the pins 25 with the back edge of the book in alinement with the shafts of the leaf-turning arms. The leaf-turning arms are all thrown to the right-hand side of the device, and the lower edges of the leaves to be turned are successively engaged with the turning-arms, beginning with the uppermost and innermost arm, the tubular member 15 of each arm of course being adjusted so that the fingers or seats may occupy the most effective position upon the leaves according to the widths thereof, it being preferable to have each seat somewhere between the middle of the leaf and the outer free edge thereof, but not so near the edge of the leaf as to permit of the latter escaping from the seat during the turning thereof. When the leaves have been engaged with all of the arms, the keys at the right-hand side of the casing will be at their inner limits and the opposite keys at their outer limits, so that by pushing inwardly upon the keys or finger-pieces in regular succession, beginning with the lowermost key, the leaves will be quickly and effectively turned from the right to the left in their proper order. Should it be desired to repeat a portion of the music upon the leaf which has been last turned, it is apparent that said leaf may be readily returned to its original position by pressing upon the corresponding right-hand key, which has been projected by the original turning of the leaf.

Among the advantageous features of the present device the most important will be noted as follows: Means is provided for clamping the device firmly upon the music ledge or rail of a piano, so as to effectually obviate wabbling and displacement of the device during the manipulation of the leaf-turning arms, and the device is also adjustable in order that it may be conveniently fitted to pianos of different sizes. Each leaf-turning arm is mounted to turn upon an axis which is in alinement with the hinged edge of the corresponding leaf, whereby the throw of all of the arms is the same, the leaves are turned in a regular and uniform manner, and they do not slide through the seats and become loose to any appreciable extent. The seats or fingers 16 engage the lower edges of the leaves, and therefore there is no adjustment required to fit the device to different lengths of leaves, while the arms are endwise adjustable, so as to be accommodated to leaves of different width. Moreover, the shafts or journals of the arms are disposed vertically one in front of the other, and the manipulating-keys are arranged in two vertical sets at the middle of the lower portion of the device, and therefore disposed in the most convenient position and 65 are not spread over the device.

What I claim is—

1. A leaf-turning device, comprising a body,

a substantially U-shaped spring-clamp having its opposite ends connected to the back of the body near the lower end thereof, and leaf-turning means coöperating with the front of the body. 70

2. A leaf-turning device comprising a body, guides upon the back of the body, an extensible member mounted in the guides and adapted to be projected above the top of the body, a set-screw piercing the front of the body and in coöperative relation with the extensible member, and leaf-turning means coöperating with the front of the body. 75 80

3. A leaf-turning device, comprising a plate-like body, one or more stiffening-cleats secured transversely across the back of the body, the inner edge of each cleat being notched, an endwise-shiftable bar mounted 85 in the notch with its upper end adapted to be projecting above the upper end of the body, a set-screw piercing the body and in coöperative relation with the bar, and leaf-turning means coöperating with the front of the body. 90

4. A leaf-turning device, comprising a plate-like body, a substantially U-shaped spring-clamp having its opposite ends secured to the back of the body near the lower end thereof, one or more stiffening-cleats secured transversely across the back of the body, each clip having its inner edge provided with a notch, an endwise-shiftable bar working in the notch with its upper end adapted to be projected beyond the upper end of the body, a set-screw 100 piercing the body and in coöperative relation with the extensible bar, and leaf-turning means coöperating with the front of the body.

5. The combination with a musical instrument having a front pendent ledge at its top, 105 and a music-rail provided with an upstanding ledge, of a leaf-turning device comprising a body having its lower end disposed in front of and against the ledge, a clamp carried by the back of the body and engaging 110 the back of the ledge, whereby the latter is gripped between the clamp and the body, the upper end of the body being fitted back of the ledge at the top of the instrument, and leaf-turning means carried by the front of 115 the body.

6. In a leaf-turning device, the combination with a body, of a casing carried thereby, a plurality of shafts piercing the top of the casing with their upper ends projected to 120 different heights above the casing in succession from the front to the rear shafts, leaf-turning arms carried by the upper ends of the shafts and working in different planes, a stepped support having its steps disposed 125 to support and separate the arms at one limit thereof, and means for turning the shafts to swing the arms.

7. The combination with a body having a substantially horizontal transverse book-support, 130 of a casing carried by the front of the body and below the support, a series of upstanding shafts journaled in the bottom of the casing with their upper ends projected through the

top thereof and alined one in rear of the other, leaf-turning crank-arms carried by the upper ends of the shafts and working between the top of the casing and the book-support, pinions upon the shafts and disposed in different planes, a vertical series of substantially horizontal endwise - shiftable keys piercing the front of the casing and provided with teeth in mesh with the corresponding pinions, 10 and a similar series of keys at the opposite side of the series of pinions and in mesh therewith, each key having a finger-piece at its front end, and provided at its rear end with an endwise-slidable guide connection with 15 the back of the casing.

8. In a leaf-turning device, the combination with a flat body, of a transverse series of pins projected therefrom near the lower end thereof, a casing carried by the body below the pins, a plurality of upstanding rotatable shafts piercing the top of the casing and alined one in front of the other, the upper ends of the shafts being projected above the casing in a progressive succession from 25 front to rear, laterally-projected arms car-

ried by the upper ends of the shafts, tubular arm members telescoping upon the respective arms, upstanding spaced leaf - embracing spring-fingers carried by the outer ends of the tubular arm members and working between certain of the pins, pinions carried by the shafts within the casing and lying in different vertical planes, two sets of keys lying at opposite sides of the shafts and piercing the front of the casing, the corresponding 35 keys of the two sets lying in the same plane at opposite sides of and having rack-teeth in mesh with the same pinion, the outer end of each key being provided with a finger-piece, and its inner end having a longitudinal socket, 40 and pins projected forwardly from the back of the casing and into the sockets of the respective keys.

In testimony that I claim the foregoing as my own I have hereto affixed my signature in 45 the presence of two witnesses.

AL HERBERT LAMB.
